UNITED STATES PATENT OFFICE.

ARTHUR ERNEST HEATH, OF LONDON, ENGLAND.

SPARKING PLUG.

1,234,757.

Specification of Letters Patent.

Patented July 31, 1917.

Application filed November 28, 1916. Serial No. 134,081.

To all whom it may concern:

Be it known that ARTHUR ERNEST HEATH, a subject of the King of Great Britain, residing at London, England, has invented 5 certain new and useful Improvements in Sparking Plugs, of which the following is a specification.

The object of my invention is to construct a sparking plug for internal combustion engines in which the central electrode is perfectly insulated from the metal body or casing, an air space is provided within the metal body or casing and in some cases the metal body and other parts may be provided 10 with holes to allow of a current of air passing through the air space for keeping the central electrode cool.

According to my invention I construct the sparking plug from a tubular metal body formed with an enlargement or chamber at one end and a smaller chamber at the other end and with a contraction or neck between the two, an electrode having a screw thread at one end and an enlargement or 15 shoulder at the other, an insulator surrounding part of the electrode and having one portion of larger diameter than the other for fitting the smaller chamber and obtaining a seating against the contraction or neck 20 in the metal body, an air space within the larger chamber, the cap and the walls of the casing surrounding same being provided or not with holes to allow of a circulation of air within the air space, a sparking point 25 on the central electrode or on a ring held to the metal body by turning over the end, nuts engaging the central electrode for securing the cap and electrode and the bottom insulator to the metal body, and a cup shaped 30 insulating cap having its tubular portion positioned within the enlargement or chamber of the metal body and acting as an insulating apron between the metal body and the central electrode.

40 My invention will be clearly understood from the following description aided by the annexed drawings in which:

Figure 1 is a sectional elevation of a 45 sparking plug constructed according to my invention.

Fig. 2 is a plan of same.

Fig. 3 is a similar view to Fig. 1 but showing the insulator held in place by the center electrode and the metal body and cup shaped insulator provided with means for allowing of a passage of air through the air

space for cooling purposes, and with the sparking point carried by the central electrode instead of by a washer as in Fig. 1.

Fig. 4 is an elevation of Fig. 3.

According to my invention I form the tubular metal body *a* of the plug with an enlargement or chamber *b* at its top or rear end, and its bottom or front end *c*, which is screw threaded in the usual way for screwing the plug into the cylinder, is formed with a contraction or neck *d* in the form of a beveled valve seating in its bore situated between the chamber *b* in the enlarged top end of the plug and the bore in 70 the smaller bottom end.

The porcelain or other insulator *e* which surrounds or partly incloses the conductor or center electrode *f*, is formed of two diameters, the larger end of the insulator *e* fitting within the bore of the front end of the metal body *a*, to the contraction or neck *d*, at which point the insulator is narrowed in diameter so as to pass through the neck or contraction *d* when the insulator *e* is pushed 80 into the metal body *a* from the front or bottom end. The neck or contraction *d* thus forms an abutment or seat against which the larger end of the insulator *e* presses so that the shocks of the explosions will be borne by 85 the abutment formed by the contracting or seating.

The open end of the enlarged chamber *b* in the metal body *a* is closed by an insulator cup shaped cap *g* with its tubular portion *h* 90 extending within the body or shell of the metal body *a*, this extension *h* acting as an insulating apron between the shell or metal body *a* of the plug and the central electrode *f*.

The cap *g* has a central hole *i* for the passage of the screw threaded end of the electrode, and the insulator cap *g* is secured in position at the top end of the metal body *a* by a nut *j* and washers *k* on the threaded 100 end of the conductor or electrode *f*. The bottom or front end of the electrode *f* is formed with an enlarged head *l*, so that by tightening the nut *j* on the electrode *f* the insulator *e* can be drawn into the bore of the 105 metal body *a* and pressed firmly against the contracted seating *d* in a gas tight manner, the insulator *e* may also be secured and held firm in the plug by means of a washer *m* bearing on the outer edge, the end of the 110 metal body *a* of the plug being spun over to receive and retain the washer *m* and insu-

lator *e* in place, the washer carrying the 5
sparking point *n* as in Fig. 1 or I may form
the sparking point on the central electrode,
as in Fig. 3, in which case the washer is dis-
pensed with.

q is a nut and *r* is a spring washer en-
circling the electrode *f* the nut *q* securely
fixing the insulator *e* to the electrode *f*.

f is a terminal nut for connecting the
10 usual wires to the electrode.

By this construction of plug, the whole of
the parts are easily cleaned, and the enlarged
chamber *b* provides an air space surround-
15 ing the end of the insulator and a portion
of the conductor so that the heat of the metal
body of the plug is not communicated to the
porcelain insulator at that part, and to
further insure the cooling of the electrode *f*
20 and insulator *e* especially when such a plug
is used with aviation and exceptionally hot
engines I provide holes *s* in the metal casing
a and holes *t* in the cap *g* for allowing of a
free circulation of air in the space *b* and
25 between the cap and the electrode and insu-
lator *e* and to further enhance this cooling
I provide fins *w* on the metal body *a* so that
the rush of air will assist in the cooling.

What I claim is:—

A sparking plug for internal combustion

engines comprising a tubular metal body 30
formed with an upper enlarged chamber
and a lower smaller chamber with a con-
tracted neck between the two chambers, an
insulator of tubular form and of materially
less diameter than the upper chamber and 35
projecting into the latter, the lower portion
of the insulator being enlarged and snugly
fitting a portion of the wall of the smaller
chamber, an insulating cup-shaped cap fitted
into the upper end of the metal body and de- 40
pending into the chamber around the upper
end of the said insulator, and an electrode
extending through the insulator and up-
wardly through the cup-shaped insulating
cap, the upper portion of the electrode being 45
screw-threaded and engaged by a nut with-
in the cup of the said cap and also by an
upper nut having co-operative bearing with
the top of the cap, a sparking point being
located adjacent to the lower end of the in- 50
sulator.

In testimony whereof I have hereunto set
my hand in presence of two subscribing wit-
nesses.

ARTHUR ERNEST HEATH.
